LID HANDLE AND LATCH MECHANISM

Harland W. Whitmore, Kenosha, Wis., assignor
to Motor Products Corporation, Detroit, Mich.,
a corporation of New York

Application January 24, 1949, Serial No. 72,344

2 Claims. (Cl. 292—228)

1

The invention relates to handles for actuating the lids or doors of cabinets in opening or closing the same, and it is the object of the invention to obtain a construction which combines with and conceals within the handle a latching and locking mechanism.

It is a further object to obtain a construction which can be formed largely of die cast elements which can be readily assembled with each other and easily attached to the lid and cabinet.

With these objects in view, the invention consists in the construction as hereinafter set forth.

In the drawings:

Figure 1 is a vertical section partly in elevation through a portion of a cabinet and its closure lid showing my improved handle and latching mechanism attached thereto and in the closed position of the lid;

Figure 2 is a similar view of the latching mechanism detached and with the outer casing removed;

Figure 3 is a rear elevation of Figure 2;

Figure 4 is a plan view;

Figure 5 is a section on line 5—5, Figure 3.

It is one of the features of my handle and latch mechanism that when the lid or door of the cabinet is closed the latch mechanism including the keeper is completely concealed within the outer casing of the handle.

It is a further feature that this outer casing is detachable from the mechanism and may be removed therefrom while the parts are being mounted respectively on the lid and the cabinet. After such mounting in properly adjusted relation to each other, the casing can be attached and, as before stated, will completely conceal all of the other parts.

In detail A and B are members hingedly secured to each other, the former being rigidly mounted on the lid or door and the latter carrying the latch mechanism. The member B in front elevation is of an inverted T-shaped form having a substantially rectangular portion B' and a portion B² centrally thereof extending upward and inward therefrom. At its inner portion B² has formed thereon hinge eye portions B³. The portion B' is ribbed on its inner face to strengthen the same and is further provided with one or more, preferably two, inwardly extending lugs B⁴ for pivotally mounting a roller C. The member A has a flat rear face A' for bearing against the outer face of the lid, and is further bifurcated to form spaced eye portions A² which embrace the portions B³ of the member B in axial alignment therewith. The two members A and B are secured to each other by a pivot pin D, which passes longitudinally through the aligned eye portions

2

and extends outward therebeyond. On each of the outwardly extending portions is sleeved a helical spring E having arms E' and E² extending tangentially outward from opposite end portions thereof. The arm E' engages a notch or groove F in the upper face of the portion B', and the arm E² engages a notch or groove F' in the inner face of a lug A³ projecting from the end of the member A. The springs E are so tensioned as to bias the member B to swing inward or against the cabinet.

As illustrated in Fig. 1, G is a portion of the cabinet and H is a portion of the lid which in closed position seats upon the top of the cabinet. The member A is rigidly attached to the lid by bolts I which pass through apertures I' in said member and into engagement with a portion of the lid, such as the reinforcing angle member J. On the cabinet is mounted a keeper member K, which has on one portion thereof an inclined striker plate K' and beneath this a downwardly facing square shoulder K². These portions are so arranged as to be in the path of the roller C on the member B and in the closing of the lid the roller will ride over the inclined striker portion and will then move inward beneath the shoulder K². It is desirable that this keeper member should be correctly positioned on the cabinet so as to hold the lid tightly closed. Such positioning is facilitated by serrating the rear face of the keeper member, as indicated at K³, and adjustably mounting it upon a plate L mounted on the cabinet and having a serrated front face. The keeper is secured by bolts M, which pass through vertically slotted apertures K⁴ in the member K permitting a limited adjustment of the serrated faces in relation to each other.

All of the members thus far described are enclosed and concealed by a casing member N, which may be chrome plated or otherwise ornately finished. The casing can be attached to the member B after the parts of the latching mechanism have been mounted respectively on the lid and cabinet, the attachment means being screws O arranged at the bottom. The casing and also the member B are cut away centrally of the bottom portions thereof to facilitate grasping of the handle by the hand of the operator.

From the description above it will be understood that the lid or door may be actuated by the handle, and that the latter may be unlatched by drawing its lower end slightly outward to clear the keeper by the roller C. To limit the amount of angular movement permitted to the member B, the hinge eyes B³ are formed with projecting lugs B⁵ having inwardly facing shoulders

adapted to engage adjacent portions A⁴ on the member A after a predetermined angular movement such, for instance, as 15 degrees. Thus the handle may be used for lifting the lid, as well as closing it, and the tension of the springs E will produce automatic latching when the lid is closed. A key actuated locking bolt may be attached to the casing N and member B as indicated at P, being adapted to be turned into engagement with the keeper member K. Each of the members A and B and N may be formed as a die casting requiring no subsequent machining operation and capable of direct assembly with the cooperating members. This reduces manufacturing costs.

What I claim as my invention is:

1. An actuating and latching means for cabinet closures, comprising an inverted T-shaped member having the stem portion thereof projecting upward and inward and terminating in an eye portion, a stop member for attachment to said closure having bifurcated eye portions embracing and aligned with the aforesaid eye portion, a pivot pin extending through said eye portions and projecting beyond the same but within the longitudinal dimension of said inverted T-shaped member, helical springs sleeved upon said extensions, each of said springs having radially extending arms at its opposite ends engaging notched bearings in said stop and T-shaped members biasing the latter to swing inward, and a roller mounted on the inner face of said T-shaped member for cooperation with a keeper on a cabinet.
2. An actuating and latching means for cabinet closures, comprising an inverted T-shaped member having the stem portion thereof projecting upward and inward and terminating in an

5 eye portion, a stop member for attachment to said closure having bifurcated eye portions embracing and aligned with the adjacent eye portion, a pivot pin extending through said eye portions and projecting beyond the same but within the longitudinal dimension of the inverted T-shaped member, stop shoulders on said stop member and T-shaped member for limiting the angular movement thereof on said pivot pin, helical springs sleeved on said pivot pin extensions, each of said springs having radially extending arms at its opposite ends, one of said arms bearing against the head of said T-shaped member, a lug projecting from said stop member to engage 10 with its inner face the other arm of said helical spring to hold the latter normally under tension and biasing said T-shaped member to swing inward, a roller mounted on the inner face of said T-shaped member for cooperation with a keeper on a cabinet in the path of said roller, and an outer casing secured to said T-shaped member concealing all of the parts including said keeper when said roller is in latching engagement therewith.
